COLLAPSIBLE PAPERBOARD RECEPTACLE

George N. Lee, Yonkers, N. Y., assignor to Brett
Lithographing Co., Long Island City, N. Y.

Application June 30, 1941, Serial No. 400,456

7 Claims. (Cl. 206—44)

This invention relates to collapsible receptacles together with the method of setting them up, and more particularly to receptacles of this type made from a single blank of card or other suitable paper board.

The principal object of the invention is to provide a collapsible paper board article having its wall structure adapted to receive vertical pressure, after opening of the article, to thereby produce a form of receptacle having a raised pyramidal center.

Another object of the invention is to provide a collapsible paper board article which may be supplied to the trade in collapsed condition and has its wall structure so formed that it is only necessary to open the article and press the wall of the structure to set said article up in receptacle form.

It is common practice for manufacturers or distributors of goods to give to dealers display material gratis for the advertising benefits to the manufacturer or distributor. Where the dealer must assemble the display piece, it frequently occurs that difficulty is encountered and the display material discarded without producing any benefit to the dealer or the supplier. One object of this invention is to provide a display receptacle which may be placed in operative form without the necessity of connecting any parts or otherwise assembling any parts.

Another object of the invention is to provide a collapsible paper board receptacle which has a wall structure that may be distended in one direction or another in order to set up or collapse said receptacle.

Another object of the invention is to provide a collapsible paper board receptacle having relatively bendable wall forming parts which, upon opening of the receptacle, may be progressively distended into or out of said receptacle to vary the size thereof.

Another object of the invention is to provide a paper board display receptacle or basket that may be supplied to the trade in collapsed condition and which, through provision of foldable and distensible wall structure, may be readily opened and set up for use.

Another object of the invention is to provide an improved collapsible paper board display receptacle or basket and a display card therefor which may be removably installed thereon.

Another object of the invention is to provide a paper board blank having parts relatively bend-

able to form a distended interior wall structure of a receptacle made from said blank.

The invention consists of the construction, combination and arrangement of parts, as herein illustrated, described and claimed.

In the accompanying drawings, forming part of this disclosure, is illustrated one form of embodiment of the invention, in which drawings similar reference characters designate corresponding parts, and in which:

Figure 1 is a perspective view of a collapsible paper board receptacle made in accordance with the present invention;

Figure 2 is an enlarged vertical sectional view on the line 2—2 of Figure 1, looking in the direction indicated by the arrows;

Figure 3 is an enlarged plan view of a paper board blank from which the receptacle shown in Figure 1 is made;

Figure 4 is a detail perspective view of the receptacle illustrated in Figure 1, showing the same in collapsed condition;

Figure 5 is an enlarged vertical sectional view of the receptacle illustrated in Figure 4, showing the same in open condition;

Figure 6 is a view similar to Figure 5, showing a portion of the wall structure of the receptacle distended therein;

Figure 7 is a view similar to Figure 6, showing the wall structure further distended within the receptacle.

Referring to the drawings, particularly to Figure 3, the numeral 8 indicates broadly a paper board blank from which the receptacle is made. The blank 8 has formed thereon a plurality of triangular panels 9 having score lines 10 therebetween enabling said panels to be folded one with respect to another. One of the panels 9 of the blank has formed thereon flaps 11 and 12, there being a score line 13 formed on the blank between that panel and the flaps enabling said flaps to be folded relative to said panel. The flaps 11 and 12, as by application of adhesive thereto indicated at 14, are adapted to be adhesively secured to the first of the panels 9 viewed counter-clockwise from said flaps in Figure 3 of the drawings.

The apex ends of the panels 9 have extending transversely thereof, spaced parallel score lines 15 forming on the inner ends of the panels relatively bendable interconnected portions or parts 16 in the form of small strips progressively increasing in length from the center of the blank outwardly thereof. The flap 11 has extending

transversely thereof spaced parallel score lines 17 forming relatively bendable elements 18 interconnected with each other and with the parts 16 and providing continuations of the latter in the form of small strips progressively increasing in length from the center of the blank outwardly thereof. A V-shaped notch 19 is formed in the blank between the flaps 11 and 12 and extends inwardly to the score line 13.

The blank 8 has formed therein from the center thereof outwardly along the score lines 10 and 13, spaced perforations 20 and, as will clearly appear from Figure 3, the score lines 15 and 17 extend transversely of the panels 9 and the flap 11, respectively, to said perforations. The blank 8 is provided at the base or outer ends of the panels 9, with flaps 21 and score lines 22 between said panels and flaps. Also, the blank 8 has formed therein upon the score lines 22 between certain of the panels 9 and flaps 21, elongated slots 23. The blank 8 is made from a single piece of card or other suitable paper board and may be cut, scored and formed, as shown in Figure 3.

The blank 8 is initially set up by folding the panels 9 relatively and inwardly and bringing the score line 13 into alignment with the free edge of the panel 9 which, as viewed in Figure 3, is disposed at the top of said blank. At the same time, the opposed ends of the score lines 15 of that panel and the score lines 17 of the flap 11 are aligned and overlapped, whereupon the flaps 11 and 12 are adhesively secured to said panel. The flaps 21 are then folded or bent downwardly from the panels 9 along the score lines 22, thus forming an open collapsible paper board article of inverted pyramidal form such as shown in Figure 5 and indicated broadly at 24 therein.

The score lines 15 and 17 will now be disposed in fixed relation, and the relatively bendable interconnected parts 16 and 18, which are of polygonal form, will provide at the center of the article 24 a wall structure indicated broadly at 25. The downwardly folded flaps 21 will, when the article 24 is set up in receptacle form as hereinafter described, form an ornamental apron for the receptacle.

The wall structure 25, which forms the apex end portion of the article 24 may, as hereinafter described, be distended within said article to set it up in receptacle form. The blank 8 could, of course, be set up by the customer or user to form the article 24 in the manner described. It is customary, however, for the manufacturer to set up paper board blanks for formation of receptacles therefrom. Accordingly, the manufacturer will set up the blank 8 to form an open collapsible article 24 therefrom such as shown in Figure 5, whereupon he will collapse said article into the form shown in Figure 4 and ship the article to the trade in collapsed form for use by the customer.

In setting up the article 24, the customer or user first opens it into the form thereof shown in Figure 5. Then, by placing the apex end of the article upon the surface 26 of a counter or other solid support, and applying pressure downwardly on the article, as indicated by the downwardly directed arrows in Figures 5, 6 and 7, the wall structure 25 will be distended upwardly within the article to set it up in receptacle form. In this setting up operation, the perforations 20 provide for slight displacement of the paper board material located upon those portions of the score lines 10 and 13 between said perforations. This

enables the parts 16 and 18 of the wall structure 25 to readily bend relatively and upwardly and progressively enter the article 24, as indicated by the upwardly directed arrows in Figures 6 and 7, when said article is set up in receptacle form in the manner described.

All, or portions only, of the wall structure 25 may be distended within the article 24 to vary the size of the receptacle set up therefrom. Figures 10 and 7, for example, show receptacles of different heights made from the same article. Figure 7 shows, in dotted lines, the wall structure 25 distended within the article 24 to form a receptacle therefrom of another size. Figures 1 and 2 show 15 in perspective and cross-section, respectively, a form of receptacle in which the outermost polygon of the wall structure 25 and which is comprised by the outermost endwise connected parts 16 and 18, forms the base of said receptacle. 20 The outermost polygon of the wall structure 25 could, however, also be distended within the receptacle, in which case the base of the receptacle would be formed by the edge between said polygon and the upwardly and outwardly flared portions 25 of the panels 9.

The portions of the panels 9 within which the wall structure 25 is distended, form side walls 27 of the receptacle and, in the form of embodiment of the invention herein disclosed, the wall structure 25, when distended within said side walls, forms a pyramidal shaped bottom wall for said receptacle. The receptacle herein shown is of the basket type primarily for use to contain and display goods of various kinds. In this case, an 30 advertising sign or card, indicated broadly at 28 in Figures 1 and 2, may be employed in conjunction with the receptacle. The card 28 may be scored longitudinally, as at 29, to provide relatively foldable panels 30, and said card has 35 projecting from the bottom thereof, tabs 31 insertable in the slots 23 to removably position the card on the receptacle at the upper edge.

The receptacle having been set up for use as described, may at any time be collapsed and 45 stored away for future use. In this case, the card 28 is removed from the receptacle to be stored away therewith, whereupon the wall structure 25 is pressed downwardly and distended to the position shown in Figure 5. Thereupon the open 50 article 24, thus again formed, is collapsed as shown in Figure 4, for storage of said article in any convenient place.

Blanks and collapsible articles or receptacles made therefrom and embodying the present invention and particularly the distensible wall structure thereof, may be made of various shapes, forms and sizes, and while one form of embodiment of said invention has been illustrated and described herein with more or less particularity, 60 it is to be expressly understood that the invention is not limited to said form of embodiment or otherwise than by the terms of the appended claims.

Having thus fully described the invention, what 65 is claimed as new and desired to be secured by Letters Patent of the United States is:

1. A collapsible paper board receptacle made of a single blank of material shaped to produce uniform panels having longitudinal score lines therebetween, said panels each being provided 70 at their lower portions on said score lines with spaced perforations and said panels having spaced parallel score lines extending transversely thereof between said perforations providing interconnected relatively bendable parts adapted,

upon opening of the receptacle and application of pressure thereon, to be distended within said receptacle and form a portion of the wall structure thereof.

2. A collapsible paper board article adapted to be set up in receptacle form and made of a unitary blank of material having uniform symmetrical triangular panels defined by score lines therebetween, said article being provided from the apices of the panels and along said score lines with spaced perforations each of said panels having in their lower portions spaced parallel score lines extending transversely thereof between said perforations to provide interconnected relatively bendable parts adapted to yield and become upon opening of the article and application of pressure thereon distended within portions of the panels forming therewith the side and bottom walls of the receptacle.

3. A collapsible paper board receptacle made of a single blank of material having raised triangular panels denoted by score lines therebetween, said receptacle being provided from the apices of the panels along said score lines with spaced perforations in their lower portions, said panels each having spaced parallel score lines extending transversely thereof to said perforations providing parallel interconnected relatively bendable portions distensible within the receptacle and forming the bottom thereof, said bendable portions being adapted to be reversely distended, and said panels thereafter being foldable along said first named score lines to collapse the receptacle.

4. A paper board blank adapted to be folded and set up to form a receptacle, said blank having a plurality of uniform semi-upright panels provided with score lines therebetween for forming the side walls of the receptacle, each of said panels having spaced parallel score lines extending transversely thereof constituting relatively bendable receptacle wall structure forming portions adapted to be distended in the receptacle upon formation thereof from the blank.

5. A paper board blank adapted to be folded and set up to form a receptacle, said blank hav-

ing: uniform triangular wall forming panels and score lines therebetween, perforations extending in spaced relation from the apices of the panels along said score lines, and score lines extending 10 transversely across each of the panels to said perforations providing relatively bendable parts adapted, upon folding and setting up of the blank, to be distended within portions of said panels and form therewith side and bottom walls of the receptacle.

6. A paper board blank adapted to be folded and set up to form a receptacle, said blank having: a plurality of triangular wall forming panels having score lines therebetween, and a single 15 gap between two of the panels a flap on one of the panels adjacent the gap, a score line between said flap and panel, said flap being adapted to be adhesively secured to the panel at the opposite side of the gap, perforations extending 20 in spaced relation from the apices of each of the panels along said other score lines, score lines extending transversely of the panels to said perforations providing relatively bendable parts adapted, upon folding and setting up of the 25 blank, to be distended within portions of said panels and form therewith side and bottom walls of the receptacle, foldable apron forming flaps on the bases of the panels, and sign card tab receiving slots between certain of the panels and 30 apron forming flaps.

7. A container comprising a plurality of substantially triangular segments formed from a unitary blank by radial creases into a raised circular row having a single gap, the end segments 35 being adherently connected at their adjacent margins to form a hopper, said creases being spacedly perforated along the apex portions of the segments, and creases disposed transversely of the segments between adjacent pairs of the 40 perforations whereby the apex portions of all the segments constitute pleats which may be turned inwardly and upwardly in the manner of a bellows and shape of a single pointed pyramid of variable height.

GEORGE N. LEE.
